INVENTOR.

Adolph Kellogg

UNITED STATES PATENT OFFICE.

ADOLPH VELGUTH, OF MILWAUKEE, WISCONSIN.

IMPROVED HINGE.

Specification forming part of Letters Patent No. 95,290, dated September 28, 1869.

To all whom it may concern:

Be it known that I, ADOLPH VELGUTH, of the city and county of Milwaukee, and State of Wisconsin, have invented a new and useful Improvement in Stop-Hinges; and I do hereby declare that the following is a full, clear, and exact description thereof, which will enable those skilled in the art to make and use the same, reference being had to the accompanying drawings, forming part of this specification, in which—

Figure 1 is a view of the hinge open with the stop in place. Fig. 2 is a view of the hinge with the stop out of place, same as when closed; and Fig. 3, a view of the hinge half closed.

Similar letters of reference in each of the figures indicate corresponding parts.

The object of my invention is to provide a hinge with a stop which shall hold it open, and thus hold up a table-leaf or anything else, as may be required, without the use of any other appliance for the same purpose.

A is one leaf of the hinge; B, the other leaf; C, the stop; D, the screw or rivet which holds the stop in place. E are the screw-holes through which the screws are screwed to hold the hinge in position.

Operation: Screw the hinge onto any place where wanted, the same as any other hinge, and when in its ordinary position turn the stop D round sidewise, as shown in Fig. 3. When the leaf of the table is raised, turn the stop, as shown, Fig. 1, and the leaf will be held up, as desired.

What I claim as my invention, and desire to secure by Letters Patent, is—

The swinging stop C, pivoted to the leaf of a hinge, as and for the purpose described.

ADOLPH VELGUTH.
